UNITED STATES PATENT OFFICE.

WILLIAM BECK, OF MONTREAL, CANADA.

BOX-FASTENER.

SPECIFICATION forming part of Letters Patent No. 461,091, dated October 13, 1891.

Application filed December 11, 1890. Serial No. 374,367. (No model.)

To all whom it may concern:

Be it known that I, WILLIAM BECK, of the city of Montreal, in the district of Montreal and Province of Quebec, Canada, have invented certain new and useful Improvements 5 in Box-Fasteners; and I do hereby declare that the following is a full, clear, and exact description of the same.

This invention relates to fasteners chiefly 10 for cigar-boxes and more particularly to those composed of a hook or nail-head and a perforated plate fitting over a recess in the cover, and the action of which depends upon the flexibility of the front of the box. Heretofore where a flat perforated plate has been 15 used difficulty has been experienced in disengaging the nail-head when this latter happens not to be situated quite centrally of the aperture, as it will still remain in contact 20 with the side portions of the plate. To obviate any chance of the nail-head failing to disengage I form a flange around a portion of the edge of the aperture, leaving only an 25 opening sufficient to allow of the passage of the nail-head into and out of engagement with the locking-lip.

The invention preferably embodies to a certain extent the principle of my spring-tongue fastener shown in Patent No. 449,811, issued 30 April 7, 1891, which principle is embodied in a spring-tongue that serves to press the stud on the front of the box outward, in that I curve the plate from its outer edge up to the edge of the guiding-flange and from the bottom 35 of the recess which the plate covers to coincide with the curve of the plate, so that there is an element tending to press the hook or nail-head into locking position, which is required, as the front of the box, from frequent 40 action, loses its flexibility. For full comprehension, however, of the invention reference must be had to the annexed drawings, in which like symbols indicate corresponding parts, and wherein—

Figures 1 and 2 are vertical sections of the 45 locking portions of a cigar-box, the former showing them unlocked and the latter locked; Fig. 3, a horizontal section taken above the plate to show it and the nail-head in plan view while locked; Fig. 4, a bottom view of 50 the plate, showing locking-nail in position; and Fig. 5 a perspective view of the locking-plate removed, all the above figures being enlarged for the sake of clearness.

A is the cover, and B the front side of the 55 box; C, the locking-nail in the top edge of the latter, and D the recess in the under side of the cover.

E is the perforated metal plate having 60 prongs *ee* to secure it in place over the recess D, as usual. This plate is distinguished from those hitherto used in that it has an upwardly-projecting flange F around a portion of the edge of the aperture, leaving only an opening G sufficient to allow of the passage 65 of the nail-head C into and out of engagement with the locking-lip E'. As shown, the aperture is only a trifle larger in diameter than the nail-head C, and the plate is preferably curved or bell-mouthed from its 70 outer edge into such aperture, so as in part to act similarly to my spring-tongue fastener before alluded to.

What I claim is as follows:

A box-fastener composed of a nail-head or 75 stud on the front of the box and a bell-mouth apertured plate fitted over a recess in the cover of same and having a portion of its inner contracted edge cut away to allow the nail-head to engage same, the bottom of 80 said recess being curved to coincide with the bell-mouth form of the plate and of a depth which will keep it always in contact with said nail-head, as shown and described.

WM. BECK.
